UNITED STATES PATENT OFFICE.

JOHN A. COLEMAN, OF PROVIDENCE, RHODE ISLAND.

GRINDING-MACHINE.

SPECIFICATION forming part of Letters Patent No. 376,815, dated January 24, 1888.

Application filed April 16, 1887. Serial No. 235,079. (No model.)

To all whom it may concern:

Be it known that I, JOHN A. COLEMAN, of the city and county of Providence, in the State of Rhode Island, have invented certain new and useful Improvements in Grinding-Machines; and I do hereby declare that the following specification, taken in connection with the drawings furnished and forming a part of the same, is a clear, true, and complete description of the several features of my invention.

In an application for Letters Patent filed by me May 23, 1886, Serial No. 166,434, I disclosed certain improvements in grinding-machines adapted to perform a wide range of service, and a characteristic feature in my prior machines involved extensive variations in the position of the grinding-surface, with reference to the work-supporting table; but I have now devised and organized a machine wherein the grinding-wheel is capable of being varied in position to meet varied requirements, and when set in any one position the work-supporting table can be raised and lowered to and from the grinding-surface, and also rotated for presenting the surface to be ground to said grinding-surface under widely varying conditions.

A grinding-machine embodying my improvements in their best form possesses capacities for performing a greater variety of work than any other machine known to me.

After describing my invention as illustrated in the accompanying three sheets of drawings, the features deemed novel will be duly specified in the several clauses of claim hereunto annexed.

Referring to the drawings, Figure 1 is a front elevation of a grinding-machine containing my present improvements. Fig. 2 illustrates the same partially in side view and partially in central vertical section, but without the auxiliary work-bed shown in Fig. 1. Fig. 3 is a horizontal lateral section of the same, showing the work-supporting table in top view, but without said auxiliary bed. Fig. 4 is a longitudinal vertical section of the table, showing adjacent portions of the frame and means for moving and adjusting the table in horizontal planes. Fig. 5 is a sectional view of the frame below the table, and shows the table-lifting screw and its connections in a

modified form. Fig. 6 illustrates still another modification of the table-lifting mechanism.

The frame of the machines includes a cylindrical vertical base, A, and a bracket or arm, A', extending from the base at one side upward, and thence toward and above said base. In the top of the bracket A' there is a cylindrical housing, a, within which the spindle b of the pendent grinding-wheel frame B is mounted, said spindle being much longer than said housing, threaded at its upper end, and provided with a clamping-nut, b'. Between the lower end of the housing a and a shoulder at b' on said spindle one or more round or U-shaped washers, b", are inserted, thus enabling the wheel-frame B to be not only adjusted at any desired height but relatively adjustable at its spindle. The bracket A' is constructed in two sections, the upper part being pivoted upon the lower part, as at a', the pivot being a bolt provided with a clamp-nut, a". Said upper part is also provided at its foot with a segmental gear, a', which is engaged by a worm on a crank-shaft, 75 a", thus enabling the upper part of the bracket, with the wheel-frame, to be swung in the arc of a circle for locating the grinding-wheel either coincident with the center of the table or at any desired point at one side of the center.

The grinding-wheel C is mounted in bearings in the lower end of the frame B, and is provided with a band-pulley, c.

It will be seen that the grinding-wheel mounted in its pendent frame has an unobstructed periphery below the plane of its axis, and hence it is capable of grinding in a vertical plane as well as horizontally, and also that it can be adjusted for duty in any desired position by swiveling on its stem at right angles to its axis, and also that it can be swung bodily to the right hand or the left because of its swiveled bracket, thus enabling an extraordinary wide range of duty regardless of variations in the size and shape of a forging or casting to be operated upon by the grinding-wheel.

The interior of the base A is turned out to afford a truly cylindrical space for the reception of the cylindrical shank d of the table D, so that said shank may slide freely, but in a

truly vertical line. As shown in Fig. 2, said shank *d* at its lower end has a disk, *e*, fixed therein, which is provided with a central hub having a tapped hole at *e'*, which is occupied by a screw, *f*, stepped in a suitable bearing, *f'*, and provided with collars *f''*, by which the screw is restricted to a rotative movement. An inclined crank-shaft, *g*, projects upward from near the base of said screw and outward through the base, its crank *g'* being at its outer end, and its inner end being geared to the screw by means of the bevel-gears *g''* *g'''*. As thus organized, the table is readily raised and lowered by rotating said crank-shaft. On top of said base *A* an annular bearing-surface is afforded for the annular worm-gear *h*, which snugly encircles said shank *d*, and the latter is free to slide therein; but the two are locked together against independent rotation by means of a spline, (in the gear,) which occupies the vertical groove *h'* in one side of said shank, as clearly indicated in Fig. 2. The worm-gear is prevented from rising by means of an overhanging hook, *h''*, bolted to the outer side of the upper portion of the base. A transverse worm-shaft, *i*, provided with a hand-crank, *i'*, is mounted in suitable bearings and engages with the worm-gear *h*, as clearly indicated in Fig. 2, it being apparent that by the rotation of said worm-shaft *i* the table *D* can be readily rotated.

The table *D* is necessarily complex for enabling its work-supporting surface to be moved in various directions in horizontal planes, and hence, as in my prior machines, the top of the table involves two sliding tables or beds, *k* and *l*. The lower sliding bed, *k*, is dovetailed at *k'* to the main portion *D'* of the table, which may be termed the "rotative bed," as clearly shown in Fig. 1, so as to slide to and fro therewin; and the upper sliding table or bed, *l*, is mounted upon the table *k* at right angles thereto, and slides on transverse guides *l'*, as clearly shown in Figs. 2 and 3, thus providing for all requisite movements in horizontal planes.

The sliding bed or table *k* is moved to and fro on its bearings by means of the hand-screw *k''*, occupying bearings in the table and tapped into a block, *k'''*, pendent from said bed, as shown in Fig. 4, and provided with a crank, *k''''*, as shown in Fig. 1.

The bed *l* is moved to and fro by means of a rack-gear, *l'*, on its under side and a gear, *l''*, on a shaft, *l''''*, having a crank, *l'''''*, all as clearly indicated.

The sliding bed *k* is slotted to afford proper space for the gear *l''*, and the latter is splined upon its shaft, so that it may move laterally to and fro with the bed *k*.

As thus far described, it is obvious that a rotation of the table will also cause it to rise or fall on its lifting-screw if the latter be not also rotated so as to counteract the lifting movement. In Fig. 5 I have shown the lifting-screw *f*, tapped into a globular nut, *f''*, which is non-rotative, but nevertheless will

admit of some slight variations in the position of the screw with reference to the table-shank *d*, and thus insure free and easy movements of the screw and the shank, even if their axes were not always exactly in line with each other. The disk *e* in this case is not bolted to the shank *d*, but its edge is freely confined in an annular bearing at *e'*, so that the table-shank can revolve without revolving the disk, the latter being free to rise and fall with the table, but kept from rotating by means of a guide, *e''*, bolted to the inner side of the base *A* and projecting upward through a guide-hole in said disk.

For grinding flat, beveled, or concave surfaces in annular lines or upon annular pieces of work the table is rotated and the grinding-wheel swung sufficiently away from the center to enable it to occupy the required annular path. A circular auxiliary bed is placed upon the table, as indicated in dotted lines in Fig. 3. The sliding bed *l* is locked in a truly central position on the table *D* by means of thumb-screws *k''''*, which accurately register with tapered holes in the underlying portion of the top of the table. The circular auxiliary bed referred to is secured to the table by means of bolts passing through the holes *k''''* in the sliding bed *l* and into tapped holes in the bed *k*, thus providing for securely mounting said circular bed firmly and concentrically on the table, so that with the grinding-wheel properly located and a ring-shaped piece of work properly mounted on the bed the table may be rotated and the piece to be ground presented progressively in annular lines to the grinding-surface. It is sometimes desirable that circular and to-and-fro movements be alternately employed in presenting the same piece of work, in which case the beds *k* and *l* are not locked together and to the table, the circular auxiliary bed being then secured to the bed *l* by means of bolts occupying the tapped holes *k''''*, this permitting oval work to be well presented to the grinding-surface, the complex table then containing elements essentially involved in an oval chuck. In grinding circular planes or concaves, as when rotating the table, it is generally desirable to employ a grinding-wheel having a rounded face, so that as the surface to be ground is presented laterally to the wheel the grinding-surface can operate progressively; but if the grinding is to be executed in circular lines a flat-faced grinding-wheel is preferably employed.

When my machines are desired mainly for performing such duties as will involve the rotation of the table during the grinding operation, I specially provide for said rotative movement at the lifting and supporting mechanism. The arrangement of the screw, its tap, and disk, as shown in Fig. 5, is of special value in this connection; but a still greater freedom for rotative movement is provided for in the arrangement illustrated in Fig. 6, wherein the rotative screw *f* rises and descends in its tapped bearing *f''*, which is secured to the interior of

the base A, and at its upper end it has a swivelled conical cap, f^5 , which occupies a suitable seat in a disk, e^4 , which is secured to the interior of the tubular shank d of the table. The lower end of the screw is plain, but longitudinally grooved, and a worm-gear, g^4 , is splined thereto and rotated by means of a worm on a crank-shaft, g^5 , so that the table can be easily raised and lowered. The gear g^4 is supported on a suitable bearing, which also serves as a vertical guide for the screw.

With my machine I also employ for performing certain kinds of work a longitudinally-tilting work-supporting frame, E, as an auxiliary bed, which is pivoted at one end, as at m , to the bed L, and at the opposite end is provided with an adjusting supporting-cam, n , which is rotated by means of a worm-gear and shaft, n' . This auxiliary bed is provided with suitable adjusting-centers, as at o, thus enabling axial or cylindrical pieces of work to be properly mounted. The cam will permit said auxiliary bed to occupy a horizontal position for straight cylindrical work or an inclined position for tapered work, as indicated in Fig. 1, and this latter adjustment is desirable not only for round tapered work, but also for tapered polygonal work, each variety involving merely a change in the relative positions of the surface to be ground and the grinding-wheel—as, for instance, in Fig. 1 the auxiliary bed and grinding-wheel are set for grinding a flat-surfaced taper or wedge; but if the taper is to be round the table would be rotated ninety degrees, so that the axis of the grinding-wheel would be parallel with the axis of the piece to be ground.

In my said prior application for Letters Patent certain features of invention were disclosed which have been embodied in my present machine, and certain of the features of construction and arrangement heretofore employed by me can be applied to my present machines without departure from certain portions of my present invention.

Having thus described my invention, I claim as new and desire to secure by Letters Patent—

1. In a grinding-machine, the combination,

substantially as hereinbefore described, of a sliding work-table, an overhanging grinding-wheel supported in a pendent pivoted frame, by means of which the wheel has an unobstructed periphery and is pivoted at right angles to its axis, and means for lifting and lowering said table and maintaining it in position.

2. In a grinding-machine, the combination, substantially as hereinbefore described, of a sliding work-supporting table which is non-rotative in itself, a rotative bed on which said table is mounted, a pendent grinding-wheel above said work-supporting table, and means for varying the space between the grinding-face of said wheel and the table.

3. In a grinding-machine, the combination, substantially as hereinbefore described, of a rotative bed, a work-supporting table non-rotative in itself, but fitted to a transverse slide on said bed, a pendent grinding-wheel mounted in bearings above said table and supported by a suitable bracket, and means for raising and lowering said bed and maintaining it in position.

4. In a grinding-machine, the combination, substantially as hereinbefore described, of a rotative bed, a work-table non-rotative in itself, but fitted to a transverse slide on a second sliding table interposed between said rotative bed and the work-supporting table, a pendent grinding-wheel mounted in bearings above the work-supporting table, and means for raising and lowering said bed and tables and maintaining them in position.

5. In a grinding-machine, the combination, substantially as hereinbefore described, of the grinding-wheel, the sliding table beneath said wheel, means for varying the space between the grinding-face of said wheel and the table, and a longitudinally-tilting work-supporting frame mounted upon said sliding table and supported at one end by an adjusting-cam rotatively controlled by a worm and gear.

JOHN A. COLEMAN.
